UNITED STATES PATENT OFFICE.

GEORGE H. MACLEAN, OF NEW HAVEN, CONNECTICUT.

PORTABLE TURNTABLE.

Application filed November 20, 1922. Serial No. 602,278.

To all whom it may concern:

Be it known that I, GEORGE H. MACLEAN, a citizen of the United States, residing at New Haven, in the county of New Haven 5 and State of Connecticut, have invented a new and useful Improvement in Portable Turntables; and I do hereby declare the following, when taken in connection with the accompanying drawings, and the characters 10 of reference marked thereon, to be a full, clear, and exact description of the same, and which said drawings constitute part of this application, and represent, in—

Fig. 1 a side view of a turntable constructed in accordance with my invention, and shown with the table tilted and a truck run upon it.

Fig. 2 a broken view in side elevation on a larger scale.

20 Fig. 3 a corresponding plan view.

Fig. 4 an end view looking from the right of Fig. 3.

Fig. 5 a transverse sectional view on the line 5—5 of Fig. 3.

25 This invention relates to improvements in portable turntables particularly adapted for auto trucks, and especially designed for use in road building. In road building, unless a turntable is employed, it has been necessary 30 to turn the truck around before dumping, as roads are usually built in sections—perhaps half the width of the roadway—the turning space is limited, consequently, it has been necessary to turn the truck at a 35 point some distance away from the point of dumping and back the truck to the desired point. As the work progresses, it is obvious that the turntable must be portable. In building a road, forms are usually employed 40 on opposite sides, upon which the wheels, on which the turntable is mounted, may travel, but these forms are not adapted to sustain the weight of a turntable with a truck upon it. Furthermore, it is desirable that the 45 platform should be capable of tilting from one end to the other, not only to facilitate the movement of a truck upon the platform, but to compensate for grade.

The objects of this invention are to provide 50 a portable turntable especially adapted for auto trucks, to provide means for removing the weight from the forms or wheels on which the turntable is supported, and impose it upon the roadway, and another object is to provide hydraulic control for the

platform, so that one end or the other may be raised or lowered as desired, and the invention consists in the construction as will be hereinafter described and particularly recited in the claims.

60 In carrying out my invention, I form a platform with two runways 10 and 11 formed from planking arranged between two pairs of channel irons 12 and 13. These channel irons are provided midway of their length with bearings 14 for stub-shafts 15, which are supported in bearings 16 which rest upon I-beams 17 supported by a ring 18 resting on a series of tapering rollers 19 bearing in channels 20 of a bed-piece 21. 65 The bed-piece is provided on four sides with outwardly-projecting lugs 22. Two of these lugs are suspended by clips 23 from the center of two side springs 24, the ends of which being connected with shackles 25 secured to the side-bars 26 of the frame, and the other two lugs are connected in a similar way with springs 27, the ends of which being connected with shackles 28 supported by transverse bars 29. The frame also carries driving wheels 30 driven by a worm 31 and worm-wheel 32 provided with a crank 33. The opposite end is supported by wheels 34 mounted on short axles 35 pivoted to the side-bars 26 of the frame. The inner ends of the axles are coupled by a pin 36 and slot 37 with a cross-piece 38 of a steering-handle 39. Mounted in transverse frames 40 are two pairs of cylinders 41 and 42, and pivotally mounted on the platform 90 are pistons 43 and 44, which enter the cylinders. The two pairs of cylinders are connected by a pipe 45, in which is a valve 46, the stem of which is provided with a handle 47 which extends out to one side for 95 convenience of access. Preparatory to having a truck run onto the platform, the valve 46 will be operated to permit one end of the platform to be depressed. For instance, as shown in Fig. 1, the platform at the right-hand end is depressed, so that a truck can be readily run upon the platform. When a loaded truck is run upon the platform, the weight depresses the springs 24 and 27, which permits the bed-spring to be depressed onto the ground or sub-grade, and thus relieving the wheels from the weight 100 of the load. Assuming the truck has been run onto the platform sufficiently far to over-balance the platform and bring the 110

majority of the load at the high end, the valve 46 will then be operated to allow oil from the cylinders 41 to pass to the cylinders 42 and thus gradually bring the platform to a substantially horizontal position, and when the desired position is attained, the valve will be closed to prevent further movement. The platform is then turned on the bed-piece to reverse the position of the truck.

10 The truck is then dumped either in its first position on the platform, or it may be backed to the end thereof, and, if necessary, the platform may be tilted so as to lower the rear end of the truck before dumping. After dumping, the truck will be moved so as to over-balance the platform. The valve 46 will again be operated to permit that end of the platform on which the forward end of the truck rests, to be depressed, so that the truck may run off onto the roadway in the direction in which it approached. The platform is then in position for the reception of another truck. When the truck passes off the platform, the springs react so as to lift the bed-piece above the ground, leaving the device supported by the wheels 30 and 34 by which it may be moved forward.

It will thus be seen that when a loaded truck is upon the turntable, the weight is imposed upon the ground, or sub-grade, and not upon the forms at opposite sides; and that the inclination of the truck may be changed as is necessary to permit the truck to ride upon or off from the platform, irrespective of the inclination of the grade of the roadway.

I claim:

1. In a turntable, the combination with a platform, of a bed-piece with which the platform is pivotally connected, a frame from which the bed-piece is suspended, said frame provided with wheels, and springs between the bed-piece and frame, whereby, when a load is imposed upon the platform, the springs will yield to permit the bed-piece to be depressed.

2. In a turntable, the combination with a

platform, of a bed-piece with which the platform is pivotally connected, a frame from which the bed-piece is suspended, said frame provided with wheels, springs between the bed-piece and frame, whereby, when a load is imposed upon the platform, the springs will yield to permit the bed-piece to be depressed, and hydraulic means for controlling the inclination of the platform.

3. In a turntable, the combination with a platform, of a bed-piece to which the platform is pivotally connected, of cylinders on opposite sides of the pivotal point, pistons connected with the platform and co-acting with the said cylinders, the cylinders at one side of the pivot being connected with the cylinders of the opposite side, and means interposed between the cylinders to regulate the flow of fluid between them.

4. In a turntable, the combination with a platform, of a bed-piece to which the platform is pivotally connected, of cylinders on opposite sides of the pivotal point, pistons connected with the platform and co-acting with the said cylinders, the cylinders at one side of the pivot being connected with the cylinders of the opposite side, means interposed between the cylinders to regulate the flow of fluid between them, and springs between the bed-piece and platform.

5. In a turntable, the combination with a platform, of a bed-piece with which the platform is pivotally connected, a frame supported by wheels, springs between the bed-piece and frame, permitting the bed-piece and table to be depressed, and hydraulic means to adjust the inclination of the table.

In testimony whereof, I have signed this specification in the presence of two subscribing witnesses.

GEORGE H. MACLEAN.
